UNITED STATES PATENT OFFICE.

CHARLES G. OVERMYER, OF HARTFORD CITY, INDIANA.

REVERSIBLE POT.

1,097,932.

Specification of Letters Patent. Patented May 26, 1914.

Application filed April 16, 1912. Serial No. 691,090.

To all whom it may concern:

Be it known that I, CHARLES G. OVERMYER, a citizen of the United States, residing at Hartford City, in the county of Blackford and State of Indiana, have invented certain new and useful Improvements in Reversible Pots, of which the following is a specification, reference being had therein to the accompanying drawing.

10 This invention relates to reversible pots to be used in the manufacture of window glass, and has for its object the production of an efficient pot which may be easily reversed within the furnace.

15 Another object of this invention is the production of an efficient furnace, wherein the pot may be so conveniently held as to be readily set into and removed therefrom, and also readily reversed within the furnace.

20 Still another object of this invention is the production of an efficient furnace which is provided with a top, which top will normally be held in a closed position, and may 25 be easily and quickly drawn upwardly while the pot is being reversed.

With these and other objects in view, this invention consists of certain novel constructions, combinations, and arrangements of 30 parts, as will be hereinafter fully described and claimed.

In the drawings:—Figure 1 is a perspective view of the furnace showing the pot in position. Fig. 2 is a perspective view 35 of the furnace showing the pot in a position where the same is being set into or has just been removed from the furnace. Fig. 3 is a longitudinal sectional view of the furnace showing the pot therein. Fig. 4 is a 40 central transverse section through the furnace, and pots.

Referring to the drawings by numerals, 1 designates the furnace which may be of a rectangular structure provided with an 45 open upper end within which is placed, near one end thereof, a filling block 2. This filling block is formed with the furnace so as to fit snugly around the pot when the pot is placed within the furnace. The inner 50 face is, of course, formed concave so as to receive the rounded end of the pot, and the sides of the furnace are formed so as to fit snugly around the pot as illustrated in the drawing. A door 4 is hinged to the 55 upper end of the body 1 upon the side plates

5. This door is provided with a weighted bar 6 which acts as a counterbalance therefor. A cleat 7 is carried on one end of the box 1 and this cleat 7 carries a plate 8, which plate 8 is spaced from the cleat 7 by means of the spacing block 9. This plate 8 acts as a guide for the operating lever 10, which operating lever is pivotally secured to the block 11 carried by the end of the box 1. A chain 12 connects the lever 10 to the bars 6 60 of the door 4, and it will be seen that the door may be raised and lowered through the medium of the lever 11, when so desired. A locking pin 13 is carried by the cleat 7, and projects from the end of the body 1, 65 and the lever 10 may be hooked under the pin 13 for holding the top in its upwardly extending position so that the pots may be 70 freely reversed or rotated, and set into and removed from the furnace or body 1.

The box 1 or furnace is provided with notches 14, and dove-tail filler blocks 15 adapted to fit in the sockets 14 for filling the notches above the shafts 16 of the pots to prevent the flame from coming through 80 or over the pots. The plates 17' are molded in the block 15 carried by the sockets 14 upon each side thereof and constitute means for holding the pots in engagement with the shafts 16.

The pot 17 is provided with a shoulder 85 upon its upper and lower face, and thereby forms the top of the pot 19, and a bottom 20 for the other pot. The upper face of the pot carries a pot 21, and it will, therefore, be seen that the pocket will be formed upon both the top and bottom of the pot, in such a position as to allow the pocket to come in its correct position when the pot is reversed within the furnace. The pot 90 17 is provided upon each side with a socket 22, within which socket 22 is placed a metallic lining 23. This lining 23 extends over the side edges of the pot and carries an auxiliary pocket 24 which constitutes 100 means for allowing the lifting hooks 25 to engage the same whereby the pots may be conveniently set into or removed from the furnace. The hooks 25 are provided with inwardly extending ends for fitting into 105 the sockets 24, above mentioned. The pots 17 may be made of fire clay or other suitable material which will not be affected by the heat.

The furnace is placed in such a position as 110

- to be below the conveyer rod or cable 26, and may be positioned in any desired relation thereto, but preferably the conveyer rod or cable is positioned above and a little to 5 one side of the furnace. Upon this rod or cable 26 travels a roller 27 from which roller 27 is suspended a lifting lever 28, by means of a chain 29. The hooks 25 are connected to the lever 28 by means of the chain 30. 10 It will, therefore, be seen that when it is desired to lift the pot 17 to or from the box 1, the dovetail fillers 15 may be removed from the notches 14 so as to permit the hooks to enter the notches 14 for lifting the 15 pots out of the furnace by allowing the hooks 25 to engage the sockets 24. The lever can then be operated so as to raise the pot 17 out of the box 1.
- Before the pots are set in the furnace to 20 be used, they are placed in a pot-arch and heated gradually until they are hot. The pots are then conveyed to and placed in the furnace 1 while very hot through the medium of the lever 28, and the conveyer 25 pulley 27. This operation may be very quickly and efficiently carried out through the apparatus as above set forth and illustrated for the reason that the pot may be quickly and efficiently connected to the 30 hooks 25 so as to be conveyed to the furnace. It will be seen that as soon as the hooks 25 engage the pot 17 sufficiently, the shaft 16 may be placed into the sockets 22 so that the pots are ready to be set into the furnace 35 1. From the structure illustrated and described, it will be seen that the top of the furnace will be held in a closed position, in order to confine the heat within the furnace, and since the pots will fit very closely in the 40 furnace, the heat will be prevented from coming in contact with the shafts which support the pots 17. It will be further seen that by having the pots formed as illustrated that the pots will reverse freely in a 45 furnace in which the walls are built in one or a single section surrounding them, or a solid continuous wall.
- The body 1 is provided with an opening 31 for admitting the burner pipe or other 50 fuel supply into the furnace below the pot 17. A drain opening 32 is formed in the

bottom of the furnace or box 1 as illustrated in Fig. 3.

One of the shafts 16 is provided with a plurality of ears 33, and between these ears 55 is pivotally mounted an operating handle 34. This operating handle will hold the pots firmly in their respective positions while being used and drained by swinging the handle between the pins 35, as illustrated in Fig. 2.

It will be seen that as the pot 17 is reversed within the furnace, the top 4 may be swung upwardly for the reason that the same is connected to the lever 10 by means 65 of a chain 12.

What is claimed is:—

1. A device of the character described comprising a furnace, a pot removably mounted therein, provided with a cavity at 70 opposite ends upon opposite faces thereof, means carried by said furnace and engaging said pot for reversing the same within said furnace, whereby one of said cavities may be heated while the other cavity is being 75 emptied, a hinged door overhanging said pot and adapted to be swung upwardly when said pot is reversed, a shoulder formed upon said pot for engaging said door and holding the same in spaced relation to that 80 portion of the pot extending beneath the door, and means for swinging said pot upwardly, said door being adapted to normally rest in a closed position over one end of said pot when said pot is in a horizontal 85 position within said furnace.

2. A furnace of the character described comprising a frame, a door resting upon the upper portion of said furnace and pivotally connected with one end thereof, a vertical 90 strip secured to the hinged end of said door and extending above said door, a lever pivotally connected at one end with the side of said furnace, and a flexible connection between said lever and said vertical strip 95 for raising said door.

In testimony whereof I hereunto affix my signature in presence of two witnesses.

CHARLES G. OVERMYER.
